UNITED STATES PATENT OFFICE.

EDWARD P. SHURICK, OF KNOXVILLE, TENNESSEE, ASSIGNOR OF ONE-HALF TO
SAMUEL P. BELSINGER, OF KNOXVILLE, TENNESSEE.

COMBINATION MAILING FORM.

Application filed January 11, 1922, Serial No. 528,439.

To all whom it may concern:

Be it known that I, EDWARD P. SHURICK, a citizen of the United States, residing at Knoxville, in the county of Knox, State of Tennessee, have invented certain new and useful Improvements in Combination Mailing Forms, of which the following is a description, reference being had to the accompanying drawing and to the figures of reference marked thereon.

This invention relates to paper blanks, such as letters and cards adapted to receive writing or printed indicia for mailing purposes, and with particular reference to mailing cards especially adapted for advertising purposes and the like.

One of the objects of this invention is to provide a paper blank adapted to receive indicia such as a letter or mailing card which combines all the features of the present type of letter or card and the advertising advantages of an envelope stuffer, pamphlet, booklet, leaflet or return postal card or coupon.

Another feature of this invention resides in providing a postal card with an integral portion foldable along the edge line of the card so as to overlap into the body of the card to form a booklet or leaflet adapted to receive advertising matter, or adapted to carry additional sheets or leaflets for the purpose desired.

Still another object of this invention resides in providing a mailing card with a distinctive portion of desired shape or color, which distinctive portion is formed with an extension integral with the body of the card, the extension folding along the edge of the card and into the body of the card whereby to form a folder corresponding in shape and distinctive appearance with the distinctive portion so that the mailing card appears to carry a separate booklet or leaflet.

Still another object of this invention resides in providing the above construction with an additional extension folding along the edge of the card into the folder or leaflet and adapted to be used as a return mailing card.

These and other objects will in part be obvious and will in part be hereinafter more fully disclosed.

In the drawings which show by way of

illustration one embodiment of the invention—

Figure 1 is a perspective view of the card when closed;

Fig. 2 is a section therethrough, and

Fig. 3 is a perspective view of the card when completely opened.

Referring more particularly to the accompanying drawings, the invention while equally adapted to be incorporated in the standard form of letter sheet, is herein shown in connection with a mailing card. This card comprises a single blank of suitable letter paper or paper stock, such as bristol, cover stock, enamel paper or bond paper 1, preferably foldable along one or more lines such as along the central line 2 to form a foldable card or the like in a compact mailing size as shown in Fig. 1. The upper portion of the blank shown in Fig. 3 is adapted to be used for the address of the card. This face is shown as at 3 in Fig. 1. The obverse face of the card 1 as shown in Fig. 3 is adapted to be used as a letter, for advertising purposes, or for any printed or written matter, or in fact, for any purpose. In the present instance, the blank is shown as adapted for suitable advertising matter of firms sending out the blank. This card 1 is provided at any desired portion, and in the present instance, the lower left-hand portion of the card is selected as an illustration, with a distinctive portion or isolated portion 4 which is provided with an extension 5 of suitable length so as to provide the desired number of folds integral or of one piece therewith. Preferably this extension 5 folds along the edge line 6 of the card into the body of the card so as to form a leaflet or folder. The portion 4 is given different distinctive appearances by being tinted, or by different color, or is isolated from the main body of the card 1 by ruled lines or by spaces, or in fact, in any manner. So also this distinctive portion 4 may assume any shape, this latter being particularly desirable where the advertisement pertains to the shape of any commodity, such as a bottle of liquor to be advertised, a phonograph or what not. In this case, the extension 5 is preferably of the same shape and size. It will be noted that this extension 5 when it folds over

on to or within the marginal lines of the portion 4 forms a complete cover so that the portions 4 and 5 together with the reverse side of the portion 5 form, in fact, a 5 distinct booklet or leaflet, which, while being integral or of the same piece with the blank 1, yet appears to have a separate identity.

These portions 4 and 5 are adapted for 10 any type of advertising purpose, and to this end, may be printed, lithographed, colored, and may contain indicia or any matter desired. The reverse side of the extension 5 may also be correspondingly used 15 for this purpose.

In certain aspects of the invention, it is desirable to provide the portions 4 and 5 with additional leaves or sheets. In the present instance, the card is provided with 20 a sheet 6 folded centrally along a line 7, and fastened by means of staples 8. This sheet forms two leaves which correspond in shape and size with the portions 4 and 5.

Obviously any number of leaves may be 25 used and any means may be availed of for attaching to the extension 4. If desired, instead of using a separate number of leaves, a single sheet or sheets may be used which are adapted to carry samples of the commodity to be advertised. The extensions 30 4 and 5 may also be used as a catalogue or price list of the commodity to be advertised.

In case it be desired to incorporate a 35 return post-card, with the card 1, the body of the card 1 is provided with an integral or same-piece extension of suitable size and shape for this purpose. Preferably, the lower left-hand or isolated portion of the 40 card is provided with the integral extension 9 foldable along the bottom marginal line 10 of the card. This extension 9 is preferably of size and shape to fold backwardly into the distinctive or isolated portion 4 45 of the card so as to be covered and held in position when the extension 5 is also folded into the body of the card. And the two extensions 5 and 9 are in turn held in overlapping position between the main folds 50 of the blank formed by the fold line 2. This extension 9 is provided with suitable matter as in the case of ordinary return post cards or coupons. From the foregoing description it is manifest that this isolated 55 portion 4 of the blank is provided with or integrally supports a plurality, two in the present instance, of distinctive flaps or extensions which are of the same-piece with the blank.

60 It will be noted that the above described invention embodies a very simple postal form, which provides all the advantages of the post card or letter with the benefits of the booklet, folder, leaflet, or envelope stuffer, and return card and coupon. One of

the main advantages being that the booklet, catalogue, or price list carried by the post card will not become detached or lost when it is read by the receiver.

In certain aspects of the invention it is 70 desirable to perforate the line or division separating the letterhead from the envelope stuffer portions 4 and 5 of the extension so that if desirable the folder or envelope stuffer may be bodily detached from the 75 letterhead proper for filing purposes.

Obviously, many variations of the embodiment illustrated are within the contemplation of the invention, and it is not desired to restrict the invention to the precise 80 form illustrated or described, except in so far as it is limited by the scope of the appended claims.

Having thus described the invention, what I claim as new and desire to secure by 85 Letters-Patent, is—

1. A single paper blank having suitable indicia on one face thereof and adapted to be folded to a more compact size for mailing, one face of said blank having an isolated 90 indicia bearing portion lying between a fold line and the marginal line of the blank, said isolated portion integrally supporting a plurality of flaps or extensions adapted to fold one upon the other within the marginal 95 line of said isolated portion of said blank and provided with desired indicia.

2. An article of manufacture comprising an integral paper blank adapted to be folded to more compact size suitable for mailing 100 and adapted to receive indicia on one face thereof, said blank having on such face an isolated indicia-bearing portion and said blank being cut and arranged to provide two flaps foldable the one upon the other substantially into the isolated portion of said blank and provided with desired indicia.

3. A device of the class described comprising a single paper blank foldable to provide a more compact mailing form, said blank having an integral extension of less length than and foldable along one edge line of the blank into the limits thereof to provide a folder, and a second integral extension of less length than and foldable along another edge line of the blank and into overlapping contact with said first-mentioned inwardly folded extension.

4. A mailing device comprising a single 120 paper blank foldable to smaller size for mailing, and adapted to receive indicia on one face thereof, said face having an isolated indicia-bearing portion lying between a fold line and the margin of said blank, said isolated portion having extensions or flaps of less length than and projecting beyond each of the two marginal lines of the blank and foldable on said marginal lines into the isolated portion. 125 130

5. A mailing card comprising a single paper blank foldable substantially centrally thereof into a smaller mailing size, and provided with suitable indicia on one face thereof, said blank having an indicia-bearing extension integral with and of less length than one side of said blank and foldable along the marginal line thereof into the body of the blank between the main folds thereof. and said blank having a second indicia-bearing extension integral with and of less length than another side of said blank and foldable along the marginal line thereof into the body of the blank between the main folds thereof. 10 15

In testimony whereof, I affix my signature.

EDWARD P. SHURICK.
